UNITED STATES PATENT OFFICE.

FREDERIC E. BERTRAND, OF SWAMPSOFT, MASSACHUSETTS, ASSIGNEE, BY MESNE
ASSIGNMENTS, TO UNITED SHOE MACHINERY CORPORATION, OF PATERSON, NEW
JERSEY, A CORPORATION OF NEW JERSEY.

MACHINE FOR OPERATING ON INSOLES.

1,272,901.

Specification of Letters Patent. Patented July 16, 1918.

Application filed September 25, 1911. Serial No. 651,056.

To all whom it may concern:

Be it known that I, FREDERIC E. BERTRAND, a citizen of the United States, residing at Swampscott, in the county of Essex and State of Massachusetts, have invented 5 certain new and useful Improvements in Machines for Operating on Insoles; and I do hereby declare the following to be a full, clear, and exact description of the invention, 10 which as will enable others skilled in the art to which it appertains to make and use the same.

The present invention relates to machines 15 for operating on insoles which are used in the manufacture of boots and shoes, and more particularly to machines for operating on reinforced insoles to make what are known commercially as "Gem" insoles.

The process of making the insole disclosed 20 in the following description is not claimed herein because it is claimed in applicant's co-pending application Serial No. 54,765, filed October 8, 1915 as a division from this application.

One object of the present invention is to 25 provide a novel construction and arrangement of devices for forming a bead or crimp in the reinforcing material and securing it to the insole whereby the proper and uniform shaping and securing of the reinforcing material to the insole is insured.

To the accomplishment of this object one 30 feature of the invention contemplates the provision in a machine for reinforcing insoles of a single set of coöperating devices, one device arranged in advance of another in the line of feed, and operated to continuously and progressively form a bead or crimp in the reinforcing material and secure it to the insole. This arrangement enables the devices to coöperate to compress 35 the lip from base to top and bend it inward at an inclination to the surface of the insole, which is of advantage during the last- 40 ing and sewing operation, and also enables the device acting in advance to pull the material down into the angle between the surface of the insole and the bead while the reinforcing material outside the bead is loose 45 and free from tension. It has been proposed heretofore to provide an insole reinforcing machine with a single set of rolls 50

operating upon opposite sides of the lip, but in such arrangement each tool acts to place the material operated upon by the other tool under tension so that the tools are restrained by each other under ordinary conditions from drawing the loose material into the angles between the lip and surface of the insole, and between the lip and the feather. 60 Furthermore, as the material is applied while under tension it springs away from the base of the lip when removed from the influence of the tool.

Broadly considered, any suitable form of 65 coöperating devices for continuously and progressively forming the bead in the reinforcing material and securing it to the insole may be employed as found desirable or expedient. In the preferred form of the invention the coöperating bead forming devices take the form of a roll mounted to rotate about a vertical axis, and a wheel mounted to rotate about a horizontal axis, 70 said roll being arranged in advance in the line of feed of the vertical plane passing through the axis of the wheel. This construction forms an important feature of the invention.

A further feature of the invention contemplates the provision, in a machine for applying reinforcing material to insoles, of 80 a support for the reinforcing material arranged to continuously engage the outside surface of the lip, above the feather and below the reinforcing material, and constructed with a supporting face projecting inward over the lip and a face sloping toward the outside forming device, and reciprocated to cause the sloping face to push the loose reinforcing material toward the tools so that the reinforcing material may be operated upon without danger of its becoming pressed 85 down upon the insole in a plait or fold. Preferably the reciprocating support is 90 mounted to automatically adapt itself to the curvature of that portion of the lip with which it has engagement. The support is thus maintained normal to the lip throughout its varying curvatures. This arrangement insures that the support will always 95 reciprocate parallel to the lip which is of advantage in that it enables the support to properly push the material toward the tools 100

along all portions of the lip without danger of the material becoming pushed into a fold beneath the tools.

Another object of the invention is to design a machine which will provide for trimming the reinforcing fabric applied to an insole along a line on the feather inside of the edge of the insole blank so that after incorporation of the finished insole in a shoe it will not be unsightly by reason of a showing of the edge of the fabric beyond the edge of the body portion of the insole.

In accordance with this object a further feature of the invention contemplates the provision in a machine adapted to operate on the marginal portion of an insole of a fabric severing knife constructed and arranged to incise the fabric along such a line that the trimmed edge of the fabric is spaced from the edge of the insole blank. An important advantage of this construction resides in the employment of such a construction and arrangement that the fabric is severed without removing any of the stock of the feather whereby, in the completed insole, the full strength of the feather is preserved. Other advantages of this feature of the invention are explained in the following description.

These and other features of the invention, including certain details of construction and combinations of parts, will be further explained in the following description, and then particularly pointed out in the appended claims.

The various features of the present invention will be readily understood from an inspection of the accompanying drawings, in which Figure 1 is a front elevation of a machine for reinforcing insoles embodying the features of the invention in the best form at present devised;

Fig. 2 is a side elevation;

Figs. 3, 4, and 5 are diagrammatical views illustrating the relative position of the reinforcing and associated devices at different parts of the insole; and

Fig. 6 is a detail showing the co-operating reinforcing devices operating upon an insole mounted on a work support.

In the embodiment of the invention illustrated in the drawings the work support, upon which the grain side of the insole rests during the operation of the machine, consists of a slightly convex, circular table 1 mounted upon the upper end of a stem 2 which is rotatably and slidably mounted in bearing blocks 3 carried by the machine frame. The stem is splined to a sleeve 4 mounted for rotation between the bearing blocks 3. The work support is positively driven during the operation of the machine through a spiral gear 5 formed on the sleeve 4, and engaged by a spiral gear 6 secured to the forward end of a horizontal shaft 7.

The other end of the shaft 7 carries a gear 8 which meshes with a large gear 9 carried by an intermediate shaft 10. The gear 9 is engaged by a pinion 11 secured to a shaft 12 which is driven from a suitable source of power through a belt pulley 13. The work support is forced upwardly by means of a coiled spring 14 which is interposed between an adjustable plate 15 carried by a block 16 on the machine frame, and a lug 17 on the vertical arm of a bell crank lever 18 which is pivoted on a rod 19 carried by the frame. The horizontal arm of the bell crank lever is provided with a hub 20 which fits over a pin 21 carried by a horizontal slide 22 mounted to slide in guideways 23 on a head 24. The head 24 is clamped between a shoulder 25 on the stem 2 and a split clamp 26 surrounding a reduced portion 27 of the stem. This portion of the stem 2 is suitably connected to a treadle (not shown). Through the connections described the work support is normally maintained elevated by the spring 14 and is depressed through the treadle connections against the pressure of the spring 14 when it is desired to insert or remove the work. In order to prevent binding of the work support as it slides through the bearing blocks and sleeve, the spring 14, bell crank lever, and connections are duplicated as shown in Fig. 1. The upward movement of the work support under the influence of the springs 14 is limited by an adjustable stop screw 28 which is arranged to engage a lug 29 on the horizontal arm of the bell crank lever 18.

The devices for operating on the insole supported on the work supporting table to crimp the reinforcing material into a bead and cause the reinforcing fabric to adhere to the vertical lip of the insole consist of an inside former comprising a roll 29^a (see Fig. 2) arranged to press the reinforcing material against the inner surface of the lip and against the surface of the insole at the base of the lip, and an outside former comprising a rotary wheel 30 arranged to press the reinforcing material against the outer surface of the lip and against the surface of the feather. The roll 29^a is mounted upon the lower end of a vertical shaft 31 which is rotatably and slidably mounted in bearing blocks 32 carried by a horizontal slide 33. The slide 33 is held for sliding movement between gibs 34, in a guideway 35 formed on the machine frame, by a cover plate 36. The slide 33 is spring pressed in a direction tending to force the roll 29^a yielding against the inside of the lip by means of a looped spring 37 one end of which is adjustably secured to a sleeve 38 carried on the cover plate 36, and the other end of which is inserted in a hole 39 drilled in the side of the slide 33 (Fig. 2). In order to limit the inward movement of the

roll 29^a under the influence of the spring 37 the machine frame is provided with an adjustable stop 40 arranged to engage a lug 41 (Fig. 1) carried by the upper bearing block 32. The shaft 31 is forced downward so as to press the roll firmly against the surface of the sole by a looped spring 42, one end of which is adjustably mounted in a socket 43 in the upper bearing block 32 and the other end of which engages a groove 44 in a block 45 which is clamped to the upper end of the shaft 31.

The outside forming wheel 30 is secured on the forward end of the intermediate shaft 10 and is positively rotated during the operation of the machine through the connections, heretofore described, to the shaft 10 from the driving shaft 12. The rotary wheel 30 is beveled so that its lip engaging surface inclines inward toward the medial line of the sole (see Fig. 2). The roll 29^a is preferably frusto-conical in shape and is arranged with its larger base directed toward the surface of the insole so that its operating periphery is substantially parallel to the engaging surface of the forming wheel. With the forming wheel and roll thus constructed and arranged, they will act to compress the lip from base to top and bend the lip inward at an inclination to the surface of the sole, so that it will stand at the proper angle to the bottom of the last for the convenient and proper lasting and sewing of the shoe when the sole is bent transversely in applying it to the curved bottom of the last. This arrangement of the lip engaging surface of the roll and forming wheel also insures the shaping and bending of the lip and reinforcing material so that the reinforcing material is pressed firmly into the angle between the feather and the base of the lip.

The roll 29^a may be mounted to rotate freely about its axis as the sole is advanced, but it is preferred to drive the roll so that it will assist in feeding forward the work. As a further aid in feeding the work the periphery of the roll is provided with longitudinal teeth. The rotation of the roll also increases its efficiency in properly pressing the reinforcing material against the inner surface of the lip and against the sole at the base of the lip. In the construction shown the roll shaft 31 is splined intermediate its ends within a sleeve 46 mounted between the bearing blocks 32. The roll is positively driven through a spiral gear 48 secured to the forward end of the main shaft 12. While the conical roll 29^a and forming wheel 30 cooperate to compress the lip from base to top and bend the lip inward at an inclination to the surface of the insole, it will be noticed from an inspection of Fig. 1 that the axis of rotation of the roll 29^a is slightly

in advance in the line of feed of the axis of rotation of the forming wheel 30. It is therefore evident (see Fig. 2) that the roll 29^a operates to press the reinforcing material against the inner surface of the lip at a time when the reinforcing material is loose and free to move inward under the pressure of the roll. It is also evident, if the roll and wheel operated directly on opposite sides of the lip, that each tool would place the material operated upon by the other tool under tension, so that the tools would not be able to properly apply the reinforcing material into the angle between the surface of the insole and the base of the lip. With the tools operating upon the work when the reinforcing material is under tension there is great danger that the material will spring away from the lip and feather after the lip has passed between the tools. By arranging the inside roll in the manner described the reinforcing material is drawn by the roll without strain into the angle between the surface of the insole and the base of the lip and properly stuck to the inner surface of the lip from base to top through the pressure derived from the springs 37 and 42. The wheel 30 then presses the free portions of the reinforcing material down over the lip into the angle between the feather and the base of the lip and against the surface of the feather without placing sufficient strain upon the reinforcing material secured to the insole by the roll 29^a to loosen the adhesion of the reinforcing material to the insole. The material attached to the insole within the lip is, therefore, securely held by the roll 29^a from displacement under the tension of the wheel 30. As the reinforcing material is, in the machine illustrated in the drawings, applied when the reinforcing material is free to be pulled into the proper reinforcing position, there is no danger that the material will spring away from the lip and feather when the insole is fed beyond the influence of the roll 29^a and wheel 30.

The reinforcing material upon which the machine operates is very sticky, and in order to prevent the material sticking to the lip and feather prior to the operation of the reinforcing tools, the machine illustrated in the drawing is provided with a support 49 arranged in advance of the roll and wheel at the outside of the lip and above the feather and below the reinforcing material. The support is provided with a lip engaging surface (see Fig. 2), a flat top projecting inward over the lip, upon which the reinforcing material is supported clear of the lip, and a face sloping toward the wheel 30 as shown in Fig. 1. The support is carried by an arm 50 which is bent inward, then downward, and then outward to clear the edge of the work support. The arm 50 is carried by a vertical rod 51 which is loosely

mounted within a socket formed in a block 52. The block 52 is pivoted in a yoke 53, and is forced in a direction to maintain the lip engaging surface of the support yieldingly pressed against the outer side of the lip by a looped spring 54, one end of which engages a socket in the yoke, and the other end of which presses against a pin 55 on the block 52. The rod 51 is screw threaded for a portion of its length and this portion of the rod is engaged by a nut 56 loosely mounted within a slot formed in the block. The nut is provided with a series of holes which may be engaged by a suitable tool and the nut rotated so that the vertical height of the support may be adjusted. In order to permit the unobstructed removal and insertion of the work from the machine, it is desirable to move the support 49 out of operative position when the work support is lowered. To this end the lower portion of the block 52 carries an adjustable screw 57 arranged to engage a lug 58 carried by the vertical arm of the bell crank lever 18, the arrangement being such that upon depression of the work support by the treadle connections to the stem 2 the bell crank lever 18 turns the block about its pivotal connection with the yoke 53, and thus removes the arm from operative position simultaneously with the lowering of the work support. When the work has been placed in position upon the work supporting table 1 and the treadle is released, the parts return to their normal position, and the spring 54 acts to force the support 49 against the outer side of the lip.

As heretofore pointed out the reinforcing material upon which the machine operates is exceedingly sticky, and so there is a tendency for the loose reinforcing material to stick to the support as the insole and reinforcing material are fed past the support. When the loose reinforcing material sticks to the support its feed is retarded and that portion of the material being operated upon is dragged into a wrinkled and plaited condition beneath the tools, resulting in the production of an imperfectly reinforced insole. In order that the loose sticky reinforcing material may be delivered properly to the tools so that it may be secured to the insole without crease or fold, the support 49 is rapidly reciprocated in a direction substantially parallel to the lip during the feed of the insole to cause the sloping face of the support to push the material toward the tools. In the construction shown, the yoke 53 is carried on the forward end of a horizontal shaft 54^a mounted for oscillation in a bearing 55^a formed in the machine frame. The shaft 54^a carries at its rear end an arm 56^a which is provided near its upper end with a boss 57^a. The arm is rapidly

oscillated from an eccentric 58^a upon an independent power shaft 59 through a link 60, one end of which is pivoted to the boss 57^a, and the other end of which is connected to the strap of the eccentric. Through these connections the support 49 is rapidly reciprocated during the operation of the machine and thus pushes the reinforcing material into position for the operation of the tools so that the tools may properly apply the reinforcing material to the insole without crease or fold.

Fig. 3 shows the relative position of the conical roll 29^a, forming wheel 30, and reciprocating support 49 when operating to apply the reinforcing material on the substantially straight portion of the lip. As shown the support is normal to the surface of the lip so that the path of reciprocation of the support is parallel to the lip. If this relative position of the roll, wheel, and support was fixed when the point of operation was transferred around the toe and the curves at the shank the path of reciprocation would be oblique to the lip. Consequently instead of pushing the reinforcing material toward the wheel 30 so that the material would be properly pressed down on the lip and feather without crease or fold, the angular path of reciprocation would cause the material to be pushed into a fold beneath the wheel 30, with the result that a plait of material would be formed on the feather. It is therefore desirable that the support 49 be maintained normal to the outer side of the lip as the point of operation of the tools is transferred along the reverse curves of the lip at the shank and around the toe. To this end a spring 59^a is coiled around the rod 51. One end of the spring is inserted in a socket in the block 52, and the other end of the spring is held behind the arm 50. As the rod is loosely mounted in the block 52, the spring 59^a causes the support to swing to adjust itself automatically to that portion of the lip with which it has engagement. The support is therefore maintained normal to the outer side of the lip as the point of operation is transferred along the lip.

It is desirable, from a selling point of view, that the reinforcing material be trimmed on the feather, at the shank at least, along a line located within the edge of the insole. In the illustrated embodiment of the invention a trimming knife 61 is carried by a yoke 62 provided with hubs 63 and 64 loosely mounted on the forming wheel shaft 10. The knife is mounted in grooves formed in the hub 63. The position of the knife may be adjusted, in order to cut through different thicknesses of reinforcing material, by a thumb screw 64, the head of which engages a slot 65 in the knife, and the shank

of which threads into a lug 66 on the hub 63. The trimming knife 61 is rigidly held in adjusted position by a binding screw 67 carried by the hub 63. The knife is angularly arranged in the hub 63 with its cutting edge acting to cut the reinforcing material at a point directly adjacent the outside edge of the wheel 30 in the vertical plane passing through the axis of the wheel. As the reinforcing material is firmly pressed at that point between the work support 1 and wheel 30 by the springs 14, the knife 61 is enabled to cleanly sever the material along a line determined by the outside edge of the wheel. The wheel 30 thus performs the function of a sole gage to determine the location of the line of severance relative to the sole edge. As heretofore pointed out, it is desirable to trim the reinforcing material on the feather, at the shank at least, along a line located within the edge of the insole. The machine of the drawings is designed to operate upon different styles of insoles and to that end a series of wheels 30 of different widths are provided with the machine, provision being made for quickly attaching and detaching each wheel from the shaft 10. In operating upon a particular style of insole a forming wheel having a width approximating to the narrowest width of the feather is selected and secured to the shaft 10. As the width of the feather usually is narrowest at the ball portion of the insole it is evident that the gaging function of the wheel 30 provides for a severance of the reinforcing material along a line on the feather, at the shank portion at least, within the edge of the insole. The trimming knife is rapidly oscillated during the operation of the machine, and in order to insure a uniform depth of cut, the cutting edge of the knife is formed on a curve having the axis of oscillation of the knife as a center (see dotted lines, Fig. 1). As shown particularly in this figure the weight of the knife, the knife block, and adjustable connections is counterbalanced by the weight of the yoke 62. The hub 63 is provided with a toothed segment 68 (Fig. 1) which is engaged by a toothed segment 69 carried in a socket 70 formed in the end of the arm 56. The segment 69 is adjustably carried in the socket so that the proper engagement of the teeth of the segments 68 and 69 may be effected. Through these connections the knife is rapidly oscillated during the operation of the machine simultaneously with the support 49. The insole is fed through the machine by the cooperation of the rotary work support 1, the rotary conical roll 29^a, and the rotary forming wheel 30. Referring to Figs. 3, 4, and 5 it is seen that the lip of the insole is yieldingly held between the conical roll 29^a, forming wheel 30, and support 49, so that the lip is guided as it is fed at three separated points, one point lying within the lip, and the other points outside the lip. By so guiding the lip the insole is swung automatically as it is fed to transfer the point of operation of the tools around the toe, and along the reverse curves of the shank. As the outside portion of the lip is guided by means of the two tools 30 and 49, the axis about which the sole swings passes through the point of engagement of the lip with the third member which in the illustrated embodiment of the invention is the surface of the conical roll 29^a.

Certain features of the invention, for example the structural features of the canvas trimming device, are not limited to use in a machine for applying reinforcing fabric but, as will readily be understood by those skilled in the art, may be used in a machine for operating on an insole after the fabric has been applied.

During the course of the preceding description, and in the following claims, it has been convenient to employ various terms denoting direction of movement, position and the like, but it is to be understood that these terms are not expressive of any characteristic features of the invention, as it is the relative arrangement of the parts which is of importance.

While it is preferred to employ the specific construction and arrangement of the parts shown and described, it will be understood that this construction and arrangement is not essential, nor is the conjoint use of all the features of the invention essential, except so far as specified in the appended claims, and it may be varied or modified without departing from the broader features of the invention.

What is claimed as new, is:—

1. A machine for reinforcing insoles, having, in combination, a work support, and a single pair of inside and outside forming devices arranged to operate on an insole mounted on the work support, the fabric engaging and forming portion of one device being a material distance in advance of the fabric engaging and forming portion of the other in the line of feed, to continuously and progressively form a bead or crimp in the reinforcing fabric and secure it to the insole, substantially as described.
2. A machine for reinforcing insoles, having, in combination, a work support, a device for continuously and progressively pressing the reinforcing fabric against the inside surface of the lip of an insole mounted on the work support, a second device for continuously and progressively pressing the fabric against the outside surface of the lip, said devices being arranged one behind the other in the line of feed to act in succession.

- to secure the material to the insole, a support for the loose reinforcing material, and means for causing said support to advance the loose fabric toward said devices, substantially as described.
3. A machine for reinforcing insoles, having, in combination, a work support, and means for crimping the reinforcing material into a bead bent inward at an inclination to the sole, said means acting to secure the material to the surface of the insole inside the bead prior to securing the material to the surface of the insole outside the bead, substantially as described.
4. A machine for reinforcing insoles, having, in combination, a work support, and a pair of rotary tools for crimping the reinforcing material into a bead, said tools having complementary inclined faces adapted to engage the bead from base to top and bend it inward at an inclination to the insole and operating with the bead between them, one in advance of the other, substantially as described.
5. A machine for reinforcing insoles, having, in combination, a work support and a coöperating roll and pressure device for bending and shaping the reinforcing material about the lip, said roll being arranged in advance, in the line of feed, of the pressure device and operating to secure the material to the insole in advance of the securing operation of the pressure device, substantially as described.
6. A machine for reinforcing insoles, having, in combination, a work support, and a coöperating roll and wheel for bending and shaping the reinforcing material about the lip, compressing the lip from base to top, and bending the lip inward at an inclination to the surface of the insole, said roll operating to secure the material to the insole in advance of the securing operation of the wheel, substantially as described.
7. A machine for reinforcing insoles, having, in combination, a horizontal work support, a forming wheel mounted to rotate about a substantially horizontal axis and arranged to press the reinforcing material against the outer side of the lip of an insole mounted upon the work support, and a conical roll mounted to rotate about a substantially vertical axis in advance of the vertical plane passing through the axis of the wheel, and arranged to continuously press the reinforcing material against the inside of the lip, substantially as described.
8. A machine for reinforcing insoles, having, in combination, a horizontal work support, a conical roll mounted to rotate about a substantially vertical axis, and arranged to continuously press the reinforcing material against the inside of the lip of the sole supported on the work support, a forming wheel mounted to rotate about a substan-
- tially horizontal axis and arranged to press the reinforcing material against the outer side of the lip, and coöperating with the roll to compress the lip, and means for yieldingly forcing the roll toward the wheel and against the surface of the sole, substantially as described.
9. A machine for reinforcing insoles provided with a rib along the margin of the insole at varying distances from its edge, having, in combination, means for forming a bead or crimp in the reinforcing fabric and securing it over said rib to the feather, and means for trimming the reinforcing fabric as it lies on the feather a uniform distance from the rib, substantially as described.
10. An insole machine of the character described, having, in combination, means for supporting and feeding the insole and for operating on the reinforcing material at its marginal portion including an oscillating knife operating to trim the reinforcing material on the feather of the insole, at the shank portion at least, along a line spaced from the edge of the insole, substantially as described.
11. An insole machine of the character described, having, in combination, means for supporting and feeding the insole and for operating on the reinforcing material at its marginal portion, including a wheel arranged to operate upon the feather of the insole and having a width approximating the width of the feather at its narrowest part, and means for trimming the reinforcing material on the feather along a line determined by the outside edge of the wheel, substantially as described.
12. A machine for reinforcing insoles, having, in combination, means for forming a bead or crimp in the reinforcing material and securing it to the insole, including a wheel arranged to operate on the feather of the insole and having a width approximating the width of the feather at its narrowest part, and means for trimming the reinforcing material on the feather a uniform distance from the bead, substantially as described.
13. A machine for reinforcing insoles, having, in combination, means for forming a bead or crimp in the reinforcing material and securing it to the insole, including a wheel mounted to rotate about a horizontal axis, and an oscillating knife arranged to trim the reinforcing material within the edge of the sole having an edge formed on a curve having the axis of oscillation as a center, substantially as described.
14. A machine for reinforcing insoles, having, in combination, a work support, means operating upon opposite sides of the lip of an insole mounted upon the work support for bending and shaping the reinforcing material about the lip, and for feed-

ing the insole, a support for the loose reinforcing material and mechanism for rapidly reciprocating the support during the feed of the insole to cause the support to push the material into position for the operation of said means, substantially as described.

15. A machine for reinforcing insoles, having, in combination, a work support, means operating upon opposite sides of the 10 lip of an insole mounted upon the work support for bending and shaping the reinforcing material about the lip, and for feeding the insole, a support arranged in advance of said means above the feather and below the 15 reinforcing material, means for pressing the support against the outside surface of the lip, and means for rapidly reciprocating the support during the feed of the insole, substantially as described.

20. 16. A machine for reinforcing insoles, having, in combination, a work support, means for bending and shaping the reinforcing material about the lip of the insole supported on the work support, a support arranged in advance of said means above the feather and below the reinforcing material, means for pressing the support against the outside surface of the lip, means for reciprocating the support, and means for automatically swinging the support as it is reciprocated to maintain the support normal to the lip throughout the varying curvatures thereof, substantially as described.

25. 17. A machine for reinforcing insoles, having, in combination, a work support, means for bending and shaping the reinforcing material about the lip of an insole supported on the work support, a support for the loose reinforcing material and means for 30 causing the support to automatically adapt itself to that portion of the lip with which it has engagement, substantially as described.

35. 18. A machine for reinforcing insoles, having, in combination, a work support, reinforcing tools operating on opposite sides of the lip of an insole mounted on the work support, means for relatively actuating the tools and work support to transfer the point of operation of the tools along the lip, and 40 means for swinging the sole laterally about the inside tool as the point of operation is transferred along the lip, substantially as described.

45. 19. A machine for reinforcing insoles, having, in combination, a work support, a rotary roll operating inside the lip of an insole mounted on the work support, a device operating outside the lip, and coöperating with the roll to bend and shape the reinforcing material about the lip, means for 50 relatively actuating the tools and work support to transfer the point of operation of the tools along the lip, and means for swinging the sole laterally about the point of operation of the roll as the point of operation is

transferred along the lip, substantially as described.

20. In a machine for operating on reinforced insoles, an oscillating trimming knife arranged to trim the reinforcing material 70 within the edge of the sole provided with a cutting edge formed on a curve having the axis of oscillation of the knife as a center, substantially as described.

21. In a machine for operating on insoles, 75 a yoke provided with a hub mounted for oscillation, a knife block carried by the hub, a trimming knife adjustably mounted in the knife block, said yoke being arranged to counterbalance said block and knife, substantially as described.

22. A machine of the character described, having, in combination, a trimming knife, a support for the material to be trimmed, means for reciprocating the support to push 85 the material toward the knife, and means for simultaneously oscillating the knife, substantially as described.

23. A machine for applying reinforcing material to lipped insoles, having, in combination, means for forming a bead or crimp in the reinforcing material and securing it to the lip of the insole and the feather, and means for removing a portion of the reinforcing material from above the margin of 95, the feather, along the shank portion at least, of the insole, substantially as described.

24. A machine for applying reinforcing material to lipped insoles, having, in combination, bead or crimp forming tools to apply the reinforcing material to both sides of the lip and the feather, and a knife for trimming a portion of the reinforcing material from above the margin of the feather, along the shank portion at least, of the insole, substantially as described.

25. A machine for applying reinforcing material to lipped insoles, having, in combination, tools for forming and pressing the reinforcing material about the lip and on 110, the feather, and means for removing a portion of the reinforcing material from above the margin of the feather, along the shank portion at least, of the insole during the operation of said tools, substantially as described.

26. A machine for applying reinforcing material to lipped insoles, having, in combination, means for engaging the reinforcing material extending above the feather 120, and pressing it in contact therewith, and means for removing a portion of the reinforcing material from above the margin of the feather, along the shank portion at least, of the insole, substantially as described.

27. A machine for applying reinforcing material to lipped insoles, having, in combination, means for engaging the reinforcing material extending above the feather 125, and pressing it in contact therewith, and a 130

- knife coöperating with said means to trim the reinforcing material, at the shank portion at least, along a line lying within the edge of the insole, substantially as described.
- 5 28. An insole machine of the character described, having, in combination, means for supporting and feeding the insole and for operating on the reinforcing material at its marginal portion including a knife mounted above the feather of the insole, having a cutting edge projecting downward below the plane of the reinforcing material and operating to sever said reinforcing material, on the feather of the insole at the shank portion at least, along a line spaced from the edge of the insole, substantially as described.
- 10 29. An insole machine of the character described, having, in combination, means for supporting and feeding the insole and for operating on the reinforcing material at its marginal portion, including a knife extending in a plane substantially perpendicular to the plane of the insole face, having a cutting edge at its lower end below the plane of the reinforcing material and operating to sever the marginal portion of said reinforcing material from above the feather of the insole at the shank portion at least, substantially as described.
- 15 30. An insole machine of the character described, having, in combination, means for supporting and feeding the insole and for operating on the reinforcing material at its marginal portion, and a knife at substantially the point of operation of said operating means extending in a plane substantially perpendicular to the plane of the insole face, having a cutting edge at its lower end below the plane of the reinforcing material and operating to sever the marginal portion of said reinforcing material from above the feather of the insole at the shank portion at least, substantially as described.
- 20 31. A machine for operating on reinforced insoles, having, in combination, fabric trimming means, a support beneath the marginal portion of the fabric to be trimmed, and means for actuating the support in a direction to push the fabric forward for the operation of the trimming means, substantially as described.
- 25 32. An insole reinforcing machine, having, in combination, a support for the insole, a pair of rolls one inside and one outside of the rib, rotary shafts on which said rolls are mounted, means for yieldingly pressing said rolls together to grip the rib and continuously and progressively press the reinforcing fabric into position, and a knife for trimming the fabric mounted on the shaft carrying the outside roll, substantially as described.
- 30 33. An insole reinforcing machine, having, in combination, a toothed conical roll at the inside of the rib bearing with its larger base 65 on the face of the insole and with its toothed surface against the side of the rib, a roll at the outside of the rib opposite said conical roll, means for rotating said rolls, and a flat fabric trimming knife mounted against the 70 outer face of the outside roll, substantially as described.
34. A machine for trimming reinforcing fabric on insoles having a reinforced marginal lip or rib, having, in combination, 75 means for supporting and feeding the insole, a knife above the feather constructed and arranged to sever the reinforcing fabric on the feather a uniform distance from the lip or rib, and a roll bearing on the feather and 80 engaging the lip or rib to guide the insole through the machine, substantially as described.
35. A machine for operating on reinforced insoles, having, in combination, means for 85 supporting and feeding the insole, and cutting means for severing the reinforcing fabric alone along a line on the feather, at the shank portion at least, lying within the edge of the insole, substantially as described. 90
36. A machine for operating on reinforced insoles, having, in combination, means for supporting and feeding the insole, a knife above the feather for severing the reinforcing fabric, and a gage for guiding and positioning the insole beneath said knife so as to effect a severance of the fabric, at the shank portion at least, along a line within the edge of the insole, substantially as described. 95
37. A machine for trimming reinforcing 100 fabric on insoles having a reinforced marginal lip or rib and feather, having, in combination, means for supporting and feeding the insole, a knife above the feather for severing the fabric, and a sole gage coöperating 105 with the knife to cause said knife to sever the fabric as it lies on the feather a uniform distance from the lip or rib, substantially as described.
38. A machine for operating on reinforced 110 insoles, having, in combination, means for supporting and feeding the insole, cutting means for severing the reinforcing fabric extending over the feather, at the shank portion at least, along such a line that its edge 115 will lie within the edge of the insole, and mechanism for actuating said means during the cutting operation in a manner to effect a clean severance of the fabric, substantially as described. 120
39. A machine for operating on reinforced insoles, having, in combination, means for supporting and feeding the insole, a sole gage for guiding the insole through the machine, and a knife for severing the fabric 125 mounted above the insole in definite relation to said gage and spaced therefrom across the line of feed a distance to effect a severance

of the fabric, at the shank portion of the insole at least, along a line within the edge of the insole, substantially as described.

40. A machine for trimming reinforcing fabric on insoles having a reinforced marginal lip or rib, having, in combination, a sole support, a roll mounted on an axis substantially parallel to the surface of said support bearing with its circumferential surface on the feather of the insole and engaging the lip or rib with one face to guide the insole through the machine, a knife above the feather outside the roll and in definite transverse relation thereto to sever the reinforcing fabric on the feather, and means for feeding the insole, substantially as described.

41. A machine for applying reinforcing fabric to an insole, having, in combination, a support for the insole, fabric forming and pressing means comprising rolls at opposite sides of the rib, the roll at the inner side of the rib having an edge to bear in the vertex of the angle at the base of the rib, and one of said rolls having teeth for engaging the insole, means for positively driving said toothed roll to feed the insole, and a knife mounted at a definite distance from the base of the rib for trimming the fabric along a line equidistant from the base of the rib throughout its length, substantially as described.

42. A machine for preparing reinforced insoles having reinforcing fabric beaded about the lip and overlying the entire width of the feather, having, in combination, a sole support, means for rotating said support to feed the insole; and means for forcing the fabric into the angles at the base of the feather, and for operating on the fabric where it overlies the feather in a manner to position the edge of the fabric within the edge of the insole, substantially as described.

43. A machine for applying reinforcing fabric to an insole, having, in combination, means for supporting, feeding and operating upon the marginal portion of the insole, and means for removing the fabric from above the outer margin of the feather along the shank portion of the insole at least, substantially as described.

44. A machine for applying reinforcing fabric to an insole, having, in combination, means for supporting, feeding and operating upon the marginal portion of the insole, and a knife for trimming off a portion of the fabric adhering to the face of the feather along the shank portion of the insole at least, substantially as described.

45. A machine for operating on soles having a reinforced stitch receiving rib, having, in combination, a horizontal work support, a fabric pressing roll at the inner side of the rib mounted to rotate about a substantially vertical axis, a fabric pressing roll at the outer side of the rib mounted to rotate about a substantially horizontal axis, and a fabric trimming cutter above the feather having its blade mounted adjacent the outer face of said outside pressing roll, substantially as described.

46. A machine for operating on soles having a reinforced stitch receiving rib, having, in combination, a work support, power driven sole feeding rolls one on each side of the rib, and a fabric trimming knife arranged above the feather beside the roll at the outer side of the rib and having its cutting edge substantially opposite the point of pressure of said roll on the fabric, substantially as described.

FREDERIC E. BERTRAND.
